UNITED STATES PATENT OFFICE.

JAMES K. DEATON, OF CONCORD, NORTH CAROLINA.

DOUBLE CULTIVATOR.

SPECIFICATION forming part of Letters Patent No. 595,674, dated December 14, 1897.

Application filed August 16, 1897. Serial No. 648,418. (No model.)

To all whom it may concern:

Be it known that I, JAMES K. DEATON, a citizen of the United States, residing at Concord, in the county of Cabarrus and State of North Carolina, have invented new and useful Improvements in Double Cultivators, of which the following is a specification.

It is the object of my invention to provide a double cultivator having a simple and inexpensive construction and combination of parts whereby the two points from which the parallel lines of draft lead to the beams of the plows can be so adjusted as to accommodate the nature of the crops to be cultivated and at the same time control the depth of cultivation. It is my purpose, in other words, to provide a double or multiple plow cultivator having a novel construction and arrangement of the constituent parts by which crops of such a nature as to permit the use of plow-cultivators may be cultivated to any depth of soil desired and with such ease and rapidity as to enable the operation to be repeated frequently during the period of growth, thereby increasing the rapidity of development, improving the quality, and largely increasing the yield, while at the same time the expense is largely diminished, since two rows are cultivated simultaneously by two men and a single horse or mule. The importance of frequent and rapid cultivation of young crops is too well known to require any explanation.

My invention consists, to the ends specified, in the several novel features of construction and in the new combinations and arrangements of parts hereinafter fully described, and then particularly pointed out and defined in the claims which conclude this specification.

To enable others to clearly understand and to make and use my said invention, I will now proceed to describe the same in detail, reference being had for this purpose to the accompanying drawings, in which—

Figure 1 is a plan view showing a double-plow cultivator in which my invention is incorporated. Fig. 2 is a vertical section taken on the line 2 2 in Fig. 1. Fig. 3 is a perspective view, upon a larger scale, showing one of the draft connections.

The reference-numeral 1 in said drawings indicates the draft-axle, which is preferably

cylindrical in form, being conveniently constructed with the central portion of wrought-iron pipe, into the ends of which are fitted two solid extension-pieces 1^a, capable of longitudinal adjustment to adapt the plows to the width of the rows. These parts are locked in position when once adjusted by means of set-screws 2, which are tapped through the central part 1 and bear at their ends against the solid extension-pieces 1^a. The axle is supported upon suitable wheels 3 and is provided with a pair of shafts 4 or any preferred form of draft device.

Upon each of the solid extension-pieces 1^a is mounted a cuff 5, capable of a longitudinal movement upon the piece 1^a, and also having a swiveling adjustment thereon by which it may be turned or rotated in either direction. Each cuff is provided with a set-screw or set-bolt 6, by which it is firmly locked after either or both adjustments are made. Each cuff is provided with a straight arm 7 of suitable length, which projects from the cuff at a right angle to the axis of the sleeve. Upon the end of each arm is a hook 8 or an equivalent device for engaging the end of a wire rope or chain 9. Upon the central tubular portion 1 are centrally-arranged cuffs 10, from each of which projects a similar arm 12, having at its end a duplex hook or fastening 14, which holds the second end of one of the chains or wire ropes 9. I may, however, use a single hook or fastening for both.

The cultivating-plows may be of any preferred type—such, for example, as the A-frame plows shown. Each plow is connected to one of the chains 9 by means of a yoke 15, having a pulley 16, which is free to travel on the chain. By adjusting the cuffs 5 inward or toward the central cuff 10 the interval of separation between the plows may be diminished to any extent required. As the pulleys 16 travel freely on the ropes or chains 9 the line of draft will always pass through the axis of each pulley and the horizontal angle which is made by the line of draft on the plow will be the same, normally, as the draft-line upon the other side of said axle. By turning the cuffs upon the axle the arms projecting from them can be made to stand at any desired angle. For example, they may

hang straight downward and the draft-line being brought so low the plow-shovels will be caused to seek a greater depth. By adjustments between said position and a horizontal plane the depth of cultivation may be varied to any extent. Moreover, by turning the central cuff so that its arm will point upward or at a suitable angle between a horizontal and vertical line, and by giving the other cuffs such adjustment that their arms will have a suitable downward inclination, a separation between the two plows may be obtained which it is impossible to obtain by the outward movement of the cuffs. The depth of cultivation will be more or less varied by this adjustment, and it will be observed, also, that by separately adjusting the cuffs the plows may be caused to cultivate at different depths. Should the nature of the ground or the arrangement of the crops make it advisable—as, for example, where different crops are planted in alternate rows—this variation will be found to promote the convenience and rapidity of cultivation to a marked degree.

By my invention two men and one horse can easily cultivate ten to twelve acres daily, and under favorable circumstances fifteen acres would not be an excessive day's work. The plows will seek a depth which will be controlled by the position of the arms on the cuffs and will require no special attention from the operatives, who need only guide the plows. They will turn at the ends of the rows with great facility and can be drawn behind the draft-axle in going to and from the field by merely hitching the loops into the hooks or other fastenings. This will raise the nose of each plow so far that the shovels resting on the ground will slide upon those portions behind the points of said shovels.

I may evidently use three cultivating-plows instead of two without any departure from

my invention, and in some cases this change may be desirable.

45

What I claim is—

1. A cultivator consisting of a wheeled axle provided with cuffs having means for attaching the ends of chains or other flexible connections to the ends of arms projecting from said cuffs, and a plurality of plows, each having a pulley connecting it to one of said chains or connections, substantially as described.

2. In a cultivator, the combination with a wheeled axle consisting of a central piece and two end extensions, of cuffs arranged on said parts and capable of longitudinal and rotary adjustment, each cuff having a rigid arm projecting from it provided with a suitable attaching device at its end, suitable flexible connections such as chains attached to said devices, a plurality of cultivating-plows each having a pulley which rides upon one of said flexible connections, and means for fastening the cuffs when adjusted, substantially as described.

3. In a cultivator, the combination with an axle supported by wheels of separate cuffs having longitudinal and rotary adjustment thereon, a plurality of cultivating-plows each having a pulley connected to its forward end, slack flexible connections having connection to arms projecting rigidly from said cuffs each connection having one of the pulleys riding thereon, and means for locking the cuffs upon the axle, substantially as described.

In testimony whereof I have hereunto set my hand in presence of two subscribing witnesses.

JAMES K. ^{his} DEATON.
